US00D591041S

(12) **United States Design Patent**
Dickinson

(10) **Patent No.:** **US D591,041 S**
(45) **Date of Patent:** **** Apr. 28, 2009**

(54) **BAG**

(75) Inventor: **Adam Dickinson**, Lichfield (GB)

(73) Assignee: **Euro Packaging Ltd.** (GB)

(**) Term: **14 Years**

(21) Appl. No.: **29/304,842**

(22) Filed: **Mar. 7, 2008**

(30) **Foreign Application Priority Data**

Sep. 10, 2007 (EM) 000789326

(51) **LOC (9) Cl.** **03-01**

(52) **U.S. Cl.** **D3/232**

(58) **Field of Classification Search** D3/323–233,
D3/240–246, 318, 322, 324; 150/100, 103–104,
150/107–110, 114, 118–119

See application file for complete search history.
